UNITED STATES PATENT OFFICE

91,634

DESIGN FOR A TRANSOCEANIC FLYING BOAT

Lessiter C. Milburn, Towson, Md., assignor to The
Glenn L. Martin Company, Baltimore, Md.

Application May 13, 1933, Serial No. 48,113

Term of patent 14 years

To all whom it may concern:

Be it known that I, LESSITER C. MILBURN, a citizen of the United States, residing at Towson, in the county of Baltimore and State of Maryland, have invented a new, original, and ornamental Design for a Transoceanic Flying Boat, of which the following is a specification, reference being had to the accompanying drawing, forming part thereof.

Fig. 1 is a perspective view of the subject boat in flight.

Fig. 2 is a perspective view differing from Figure 1 in angularity to more clearly show the wing outlines.

Fig. 3 is a front elevation of the boat shown in Figures 1 and 2.

Fig. 4 is a side elevation of Figure 3.

Fig. 5 is a plan view of either Figure 1, 2, 3 or 4.

The dominant features of my invention comprise the seawings, the passenger body, and the wings including a plurality of leading edge mounted engines, all in ornamental relation to one another.

I claim:

The ornamental design for a transoceanic flying boat substantially as shown and described.

LESSITER C. MILBURN.
